HENRY H. PAYZANT, OF EVERETT, WASHINGTON, ASSIGNOR TO WEYERHAEUSER TIMBER COMPANY, OF TACOMA, WASHINGTON, A CORPORATION OF WASHINGTON

LUMBER PACKAGE

Application filed May 16, 1927. Serial No. 191,602.

Heretofore, the fastening means provided for bundles of lumber have not been entirely satisfactory. According to the present practice, such bundles vary in length from about 5 four to twenty-four feet and the thickness varies from about two and one-half to five inches. A bundle may comprise from three to ten or more pieces or boards laid face to face one upon another. It is a practical impossibility in the handling of such long bundles 10 to prevent bending, and during the bending the several boards in the package slip one upon another to a limited extent, because the several pieces are bent upon arcs of different 15 curvatures or radii.

Twine ties, placed at suitable intervals along the bundles, have been used for many years as the binding means. However, such ties frequently damage the lumber, particularly when used upon the softer woods. Thus, 20 during handling, the ties are often drawn so tight that they become at least partially embedded in the corners of the bundles, and where the lumber is piled to a considerable 25 height, the overlying bundles are frequently of such weight as to impress the twine into the surface of the wood upon the lower bundles. The damage thus caused has frequently rendered the goods unsaleable. Further, with 30 old methods, the ends of the boards which are carefully finished by rebutting at the mill are apt to be injured in shipping and handling. I am aware that it has been attempted heretofore to improve lumber packages by enclosing 35 the ends of the bundles within pasteboard caps, but such caps have afforded insecure protection because they have not been adapted to movably conform to the ends of the 40 boards during the bending of the bundles.

It is the object of the present invention:

First, to construct a package of this kind from durable material, so arranged as to efficiently protect the goods and thereby insure 45 delivery thereof in salable condition to dealers or other purchasers.

Second, to provide a lumber package in which the binding members are broad and flat and thus prevent the damage caused by old 50 types of tying means.

Third, to efficiently protect the ends of such bundles from injury.

Fourth, to provide lumber packages having smooth surfaces of sufficient size for labeling upon their ends, and

Fifth, to provide an end protecting cap 55 for lumber packages, which will conform to the ends of the boards and allow limited slipping of one piece upon another without danger of injury to the cap.

This invention also includes certain other 60 novel features of construction which will be more fully pointed out in the following specification and claims.

The invention will be best understood by 65 reference to the accompanying drawings in which Figure 1 is a side elevation of my improved lumber package in bent position, showing the manner in which the end caps conform to changing positions of the ends of 70 the boards; Fig. 2 is an enlarged, perspective view, showing one end of the package in normal position, with the end panel perpendicular relative to the faces of the boards; Fig. 3 is a similar perspective view of a simplified 75 form of end cap; Fig. 4 is a perspective view showing the inner binding member with the outer hinge and binding member removed; Fig. 5 shows the positions of the outer binding member and hinge before they are finally 80 secured upon the bundle; Fig. 6 is a perspective view of another form of the invention; Figs. 7 and 8 are plan views of the blanks constituting the preferred form of cap and 85 Figs. 9 and 10 are plan views of the simplified blanks.

As illustrated, my invention is primarily, although not exclusively, adapted for use in binding and protecting a plurality of boards 90 11 of equal length and width, laid face to face, one upon another, so that their ends 12 normally are in the same plane and perpendicular to the outer faces of the board.

My improved package is preferably constructed from sheet material, such as fibre or 95 box board. In the preferred embodiment, I provide an inner binding member 14 (Fig. 8), which is cut and creased to form a pair of wings 15 and a double folded, end flap 16. The side edges of the wings 15 converge out- 100

ward, and said wings are made long enough to meet, end to end, when folded about the bundle of lumber to be secured. The second blank of the preferred construction, shown in Fig. 7, has an end panel 17, formed to cap the end of the bundle, to be protected. Flaps 18 and 19 are integral with said panel 17, being creased to fold upon the outer faces of the boards. A pair of wings 20, similar to the wings 15, project laterally from the flap 18 to afford a second binding member, adapted to encircle the bundle near an end. The panel 17 also carries a pair of ears 21, arranged to be inserted between the wings 20, and lumber to complete the protection of the end corners, as hereinafter described.

In the alternate form of my device, shown in Figs. 3, 9 and 10, I provide a rectangular band 22, instead of the member 14 of the preferred construction, and a hinge member 23 (Fig. 9) having an end panel 24 and a pair of flaps 25, which correspond to the flaps 18 and 19 of the preferred construction.

To bind and protect the ends of a bundle of lumber, the inner binding member 14 is first attached, as shown in Fig. 4. Thus, the double creased flap 16 is folded over an end of one or more of the pieces of lumber and its extremity inserted between two of the boards. Now the wings 15 are folded around the bundle so as to completely embrace the same and the extremities of said wings are secured one to the other by any suitable means, such as by the tape 26, which is applied to the outer surfaces of the wings 15 to secure them together. This tape 26 may be made of suitable tough paper or fabric having adhesive on one surface for securing it in place. Obviously, other fastening means for the ends of the wings may be provided, for example, metal staples, clinched against a blade anvil inserted between the band or wings and outer board of the bundle. Now the hinge member and outer binding member may be placed upon the end of the package, as shown in Fig. 5, that is, the flap 18 is positioned to overlap the taped ends of the wings 15, and the end panel 17 is folded upon the end of the bundle. The wings 20 are then folded so as to extend about the package and outside of the wings 15. The otherwise free extremities of the wings 20 are subsequently secured one to the other by suitable means, as by tape 26. Finally, the ears 21 are folded in between the wings 20 and lumber and the flap 19 folded down upon the outer surface and secured directly to the lumber. Suitable tacks or staples (Fig. 2) may be driven to secure the flaps. Similarly, the extremity 28 of the flap 18, which projects beyond the wings 15, is secured directly to the opposite, outer face of the lumber. It will be noted that the extremities 28 and 29 of the flaps 18 and 19 respectively are cut at oblique angles relative to longitudinal corners of the package. This

facilitates sliding of one package upon another, without danger of catching the end caps of one upon the corner of another. Upon the longer bundles, I prefer to employ a band 30 of fiber board (Fig. 1), which is similar to the band shown in Fig. 10 of the alternate construction. This band 30, after being folded about the bundle, has its ends secured together in any suitable or well known manner.

It will be noted that the side edges of the wings 15 and 20, adjacent to the end corners of the package, are cut at such an angle relative to the longitudinal edges of the package, that they permit flexing of the package, as shown in Fig. 1, to the maximum extent which is likely to be required in handling.

To assemble the alternate form of the device shown in Figs. 3, 9 and 10, the band 22 is first applied to the bundle of lumber near an end and folded at the crease lines so that the ends of said band abut one against the other. These ends are now secured together by suitable means, such as the tape 31 (Fig. 3). The band 22 having been thus secured to bind the package, is positioned a short distance from the end of the bundle, as indicated in Fig. 3, and the hinge member 23 is then folded so that the panel 24 covers the ends of the boards. Finally, the flaps 25 are fastened upon the outer faces of the boards by suitable metal fasteners 32. Obviously, ears, like the ears 21 of the preferred construction, may be applied to the side edges of the panel 24 and inserted between the band 22 and lumber, if desired, to afford further protection for the end corners of the boards.

As shown in Fig. 6, it is sometimes desirable upon the shorter bundles to provide continuous protection for the outer faces of the boards. In such case, two pairs of the wings 20 may be formed on a longitudinal panel 33, which is equal in length and width to the boards of the package. Flaps 34 and 35 are also arranged to meet at the opposite side of the package, being secured to the outer board by suitable fastening means 32. Otherwise, the package shown in Fig. 6 is similar to that of the preferred construction.

It will be evident that for the lighter or less expensive bundles, the alternate form of fastenings shown in Fig. 3 may be employed, or the protection afforded by the blank shown in Fig. 7 may be applied, omitting the inner binding member 14. Further, the simplified hinge member 23 (Fig. 9) may be used in connection with the binding member 14, shown in Fig. 8. Numerous other modifications may be made within the scope of my invention, and I do not wish to limit myself to details of construction other than as pointed out in the appended claims. In some cases, as for foreign shipment, I consider it advantageous to apply tape or metal angle

clips 36 (Fig. 6) to the package to further protect the end corners during handling.

It is important to note with reference to all of the forms of the invention, above referred to, that the hinge and binding members are so arranged that the end protection movably conforms to the package, whether in normal or flat position or bent as shown in Fig. 1. Thus, the end panels 17 and 24 may be disposed either perpendicular to or at oblique angles to their attached flaps upon opposite faces of the lumber packages. All of the binding members are free upon at least one side of the package to shift longitudinally and thereby allow limited sliding of one board upon another without transmitting sheering strains to these wide bands.

Further, in all forms of the invention efficient end protection is provided, as well as smooth, firm end surfaces of sufficient size for labeling.

Having described my invention what I claim as new and desire to protect by Letters Patent is:

1. In fastening means for a bundle containing a plurality of boards disposed face to face, one upon another, the combination with a retaining band encircling said boards near an end thereof, a hinge member extending across the ends of said boards, flaps on said member positioned upon opposite outer faces of said boards, at least one of said flaps overlapping said band and means securing the otherwise free ends of said flaps upon the outer surfaces of said boards.

2. In a lumber package adapted to contain a plurality of boards laid face to face, the combination with a wide band encircling said boards near an end thereof, a hinge member extending across the ends of said boards, and arranged to flex at opposite, parallel corners of the package, flaps on said member extending upon opposite outer faces of said boards, and means securing said flaps upon the outer surfaces of said boards, said hinge member being adapted to permit limited sliding of one board upon another in the package while engaging the ends of all of said boards.

3. In a lumber package adapted to contain a plurality of boards laid face to face, the combination with a band encircling said boards, a hinge member extending across the ends of said boards and formed with a pair of parallel creases at end corners of the package, flaps on said member adapted to lie upon opposite outer faces of said boards, said flaps being freely movable one relative to the other to permit sliding movement of one board upon another and means for retaining said member upon the end of the package.

4. In a lumber package for containing a plurality of boards, the combination with a band encircling said boards, an end panel formed from fibre board and confining the ends of said boards, a pair of flaps flexibly

connected with said panel and extending upon opposite, outer surfaces of said boards, and means securing said flaps to the outer surfaces of said boards, one of said flaps being freely movable in parallel relation to the other in a direction along the package whereby limited sliding of one board upon another is permitted, and said panel may be positioned obliquely relative to said flaps.

5. In a lumber package containing a series of boards laid face to face, the combination with a binding member encircling said boards, a hinge member formed from fibre board and extending across the ends of said boards, a pair of flaps on said hinge member extending longitudinally of said boards, and means securing the ends of said flaps remote from said hinge member to the outer surfaces of said boards, said last mentioned ends being cut to extend obliquely across the boards and one of said flaps being movable longitudinally in parallel relation to the other flap, whereby limited sliding of one board upon another is permitted.

6. In a package adapted to contain a plurality of pieces of lumber, an end panel formed from fiber board and positioned upon the ends of said pieces, a pair of flaps flexibly connected with said panel and extending upon the outer surfaces of said pieces, a binding member formed integral with one of said flaps and projecting between the other flap and said pieces, and means securing said flaps upon the outer surfaces of the lumber.

7. In fastening means for a plurality of boards laid face to face, the combination with a wide binding member of fibre board encircling said boards, a hinge member covering the ends of said boards, flaps extending longitudinally of said boards and formed integral with said hinged member, at least one of said flaps overlapping said binding member and the otherwise free extremities of said flaps being secured to said boards.

8. In a package adapted to contain a plurality of boards, an end panel formed from sheet material and positioned upon the ends of said boards, a pair of flaps flexibly connected with said panel and extending upon the outer surfaces of said boards, a pair of wings formed integral with one of said flaps and projecting between the other flap and said boards, means securing said wings, end to end, about said boards, the portion of said wings between said flap and boards being free for sliding movement along the package relative to said flap and the adjacent board.

9. In a package adapted to contain a plurality of boards, an end panel formed from sheet material, positioned upon the ends of said boards, a pair of flaps flexibly connected with said panel and secured upon the outer surfaces of said boards, a binding member formed integral with one of said flaps and

extending between the other flap and said boards, a second binding formed from a separate sheet of fibre board and freely encircling the package between said first mentioned binding member and the boards, and an end flap on said second binding member projecting between said end panel and the end of a board to prevent sliding of said member away from the end of the package.

10. In a package adapted to contain a plurality of pieces of lumber, a rectangular end panel formed from fiber board, positioned upon the ends of said pieces of lumber, a pair of flaps flexibly connected to opposite sides of said panel and secured upon the outer faces of said pieces, a binding member formed integral with one of said flaps and extending between the other flap and said pieces, and a pair of ears formed on the other two sides of said end panel for insertion between said binding member and the lateral edges of said pieces, whereby the end corners of the package are protected.

11. In a package adapted to contain a plurality of boards, an end panel formed from sheet material and positioned upon the ends of said boards, a pair of flaps flexibly connected with said panel and extending upon the outer surfaces of said boards, a pair of wings formed integral with one of said flaps and projecting between the other flap and said boards, means securing said wings, end to end, about said boards, to form a binding member, the portion of said wings between said flap and boards being free for sliding movement along the package relative to said flap and the adjacent board, and a second binding member formed from a separate blank of sheet material, disposed between said wings and boards.

12. In a package adapted to contain a plurality of boards, an end panel formed from sheet material, positioned upon the ends of said boards, a pair of flaps flexibly connected with said panel and extending upon the outer faces of said boards, a binding member formed integral with one of said flaps and extending between the other flap and said boards and a second binding formed from a separate sheet of fibre board and freely encircling the package between said first mentioned binding member and the boards.

13. In a package adapted to contain a plurality of pieces of lumber, a rectangular end panel formed from fiber board, positioned upon the ends of said pieces of lumber, flaps flexibly connected to opposite sides of said panel and extending upon the outer faces of said pieces, a binding member extending between at least one of said flaps and said pieces, and a pair of ears formed on the other two sides of said end panel for insertion between said binding member and the lateral edges of said pieces, whereby the end corners of the package are protected.

14. In fastening means for a bundle containing a plurality of thin and relatively wide boards disposed one upon another, the ends of said boards being substantially flush one with another at each end, separate protective caps for each end of the bundle formed from flexible sheet material adapted to conform to said ends, a quadrilateral end panel formed on each cap to engage the ends of said boards, flaps on opposite sides of said end panel integral therewith and extending upon the outer, wide faces of two of the boards in the bundle, flaps formed on said caps to extend upon the outer edges of the boards in the bundle, said first mentioned flaps being free to change their angular positions relative to said end panels when the bundle is bent, and a binding member near each end of the bundle in engagement with the adjacent cap.

15. In fastening means for a bundle containing a plurality of thin and relatively wide boards disposed one upon another, the ends of said boards being substantially flush one with another at each end, separate protective caps for each end of the bundle formed from flexible sheet material adapted to conform to said ends, a quadrilateral end panel formed on each cap to engage the ends of said boards, flaps on opposite side edges of each of said end panels, integral therewith and extending upon the outer, wide faces of two of the boards in the bundle, said flaps being free to change their angular positions relative to said end panels when the bundle is bent, and a binding member near each end of the bundle.

16. In a lumber package, adapted to contain a plurality of boards laid face to face, the combination with a hinge member extending across the ends of said boards and formed with a pair of parallel creases at end corners of the package, flaps joined at said creases to said member and adapted to lie upon opposite outer faces of said boards, said flaps being substantially parallel one with the other and being free for limited movement in substantially parallel planes and means for retaining said member upon the end of the package.

17. In a lumber package, for a plurality of boards laid face to face, the combination with an end panel extending across the ends of said boards, flaps joined to opposite edges of said panel and extending on opposite, outer faces of said boards, said flaps being free to change their angular positions relative to the end panel, means for positively securing said flaps to the adjacent boards to thereby retain said end panel in contact with the ends of the boards when the package is distorted by bending, and a binding member confining the edges of the boards between said flaps.

In testimony whereof, I have hereunto signed my name to this specification.

HENRY H. PAYZANT.

130
